(57) **CLAIM**

The ornamental design of a adaptor for moving electrical wiring, as shown and described.

DESCRIPTION

FIG. 1 is a perspective view from above and to one side of the adaptor for moving electrical wiring, according to the new design;

FIG. 2 is a perspective view from below and to the other side thereof; and,

FIG. 3 is a side elevational view, the opposite side being a mirror image thereof.

1 Claim, 1 Drawing Sheet

FIG. 3

FIG. 2

FIG. 1
